Inventor:
Patrick J. Lucey.

UNITED STATES PATENT OFFICE.

PATRICK J. LUCEY, OF CHICAGO, ILLINOIS, ASSIGNOR TO DAVID A. WEIR, RECEIVER FOR LUCEY SLICING MACHINE CO., OF SOUTH BEND, INDIANA, A CORPORATION OF INDIANA, BANKRUPT.

SLICING MACHINE.

Application filed October 15, 1924. Serial No. 743,671.

My invention pertains to slicing machines, and more particularly to the mounting means of the slicing machine knife.

In all slicing machines of this type, now on the market, except the form of machine illustrated in this application, a knife of large diameter is used, which is necessary due to the fact that the axis of the knife of such a machine is either fixed with regard to the base of the machine or is arranged vertically above the axis of the drive sprocket for the knife and its chain, and the knife axis is only swingable on the axis of said sprocket, but is not movable longitudinally of the base, but constantly retains the radial distance from the axis of said knife to the axis of said drive sprocket; and no provision is made for use of a knife of smaller diameter for accomplishing the same results and for properly slicing material to the same effect as is done with their large knife. This objection is overcome with my improved mounting means as best shown in Fig. 1, and as may be observed therein, the center axis of the knife is placed forward from the vertical line through the axis of the drive sprocket. This arrangement makes it apparent that the knife may be decreased in radius in proportion to the distance that the center axis of said knife is placed forward from the vertical line extending through the center axis of the drive sprocket; and thus with my improved mounting means I utilize a knife of smaller diameter to the same effect and purpose as the knife of larger diameter with the usual mounting means provided on the other slicing machines on the market. Another object is to variously adjust the knife and its supporting means so as to compensate for the wearing down or receding of the knife edge, both radially and axially with respect to the movable table; and also to provide for use of knives of different shapes and convexity, and for mounting and adjusting the plane of the cutting edge of said knife either parallel to or at an angle with the side of the movable table, so as to utilize either a convex knife or a flat knife; and a further object is to mount the chain housing adjustably on the base so as to compensate for and to take up slack in said chain.

Other objects and advantages are accomplished with my invention, as will become ap-

parent from this description taken in connection with the drawing, in which,

Fig. 1 is a side elevation of a slicing machine with my invention applied thereto;

Fig. 2 is an enlarged horizontal section taken on line 2—2 of Fig. 1;

Fig. 3 is an enlarged vertical section taken on line 3—3 of Fig. 1; and

Fig. 4 is a section similar to that shown in Fig. 2, but the chain housing, which supports the knife, is shown in a slanting or tilted position, thus bringing the knife edge nearer the adjacent side or edge of the movable table.

In the drawing I have shown my invention in combination with a slicing machine of known construction, which includes a base 10 whereon is mounted a chain housing 11 used for supporting a rotatable circular knife 12. Said base is also provided with guide rods 13 on which a reciprocating table 14 moves to and fro past said knife and carries a feed plate or material holder 15 for gradually feeding material to the forward side 16 of said table as it travels adjacent said knife.

In the modern slicing machines, the circular knife is usually dished or concaved and has its peripheral edge sharpened at the convex side, as best shown in Fig. 3, to place the cutting edge adjacent the side 16 of table 14, and with such dished knives the plane of this cutting edge is generally placed parallel with said side 16; while with a flat knife the plane of the knife must be placed at an angle to said table side 16 in order to have the sharpened and beveled edge cut a straight slice from the material, because the knife gets thicker from the sharp peripheral edge towards its center.

I therefore provide an adjustable mounting means for said knife so that either the usual modern dished and concaved knife may be used and mounted parallel to the table side 16, or a flat knife may also be used with my mounting means and mounted at an angle to said table side 16, as best shown in Fig. 4. Furthermore the knife edge wears down with constant use and the repeated sharpening thereof thus decreasing the diameter of the knife, so I also provide my mounting means so that the knife may be moved and adjusted radially nearer to the approaching table to compensate for such wear. And in addition, my adjustable mounting means is arranged

to adjust the knife axially to further compensate for the receding of the knife edge in an axial direction, as best shown in Fig. 2. All this adjustment to compensate for such wear, etc., I accomplish in a very simple and inexpensive manner, and at the same time in an entirely practical and efficient manner; preferably by providing the chain housing 11, which acts as a knife support, with horizontal supporting flanges 18, and resting these upon the top of base 10, and further providing these flanges with enlarged openings or slots 19 through which loosely extend bolts 20, threaded into openings 21 in the adjacent top of base 10. I further place a disc or washer 22 between the head of a bolt 20 and the flange 18, on one side of said chain housing, and a like washer between the head of a similar bolt 20 and the bottom plate 24 of an arm 25 which supports the knife guard 26 and rests on the flange at the other side of said housing, to aid in clamping the flanges firmly in position. By loosening the bolts 20 the knife with its support, namely the chain housing, may be readily moved and adjusted axially of the knife as well as radially of said knife, as indicated in dot and dash lines in Fig. 2, to provide for a new knife or for a knife of greater convexity, and after continual use to compensate for wearing down and sharpening down of the edge of said knife, this is accomplished by moving said knife and support toward the table; and the knife and its supporting housing may also be slanted, as shown in Fig. 4, to accommodate a substantially flat knife or to turn the cutting edge of the knife to a greater advantage toward the approaching material fed by table 14 and the feed plate 15 mounted thereon. This adjustable mounting also provides means for taking up a certain amount of slack in the chain 29 by moving the chain housing 11 longitudinally of the base, as indicated in dot and dash lines in Fig. 2 by bringing the driven sprocket (not shown) which is on the knife shaft 27 at the upper part of the housing 11, forward and further out of vertical alinement with the lower or drive sprocket 28.

What I claim as my invention and desire to secure by Letters Patent is:

1. In a slicing machine having a rotary circular knife and a table movable one with respect to the other, means for adjustably mounting said knife with respect to said table

to place the plane of the cutting edge of said knife at different angles with respect to the 55 edge of said table.

2. In a slicing machine having a base with a circular knife and a support for said knife, a table movable past said knife, and means for adjusting and fastening said support on said 60 base to reset said knife in a different vertical plane with respect to the table edge.

3. In a slicing machine having a base with a dished circular knife and a table movable past said knife, flange means for supporting 65 said knife on said base, and slots with bolts of smaller diameter for adjusting and fastening said supporting means and knife axially of the knife, to compensate for the receding knife edge due to sharpening of said dished 70 knife.

4. In a slicing machine having a base with a circular knife and a support therefor, slot and bolt means for mounting said support on said base to adjust said knife axially, and to 75 swing said knife in its plane so as to set it at an angle with said base.

5. In a slicing machine having a base, a knife, and a chain housing for supporting it on said base, a table reciprocating past said 80 knife, and horizontal flanges on said housing with slots and with bolts extending loosely through said slots into said base for adjustably fastening said knife and housing on said base to adjust said knife, axially, and at an 85 angle also longitudinally of said table.

6. In a slicing machine having a base, a circular rotary knife, a chain housing for supporting said knife on said base, a table reciprocating past said knife, and horizontally 90 extending flanges on said housing with enlarged slots and with bolts of smaller diameter than said slots extending therethrough into said base for adjustably fastening said housing and knife on said base to adjust said 95 knife radially and axially of said knife or longitudinally of said base, to compensate for the receding of the knife edge due to sharpening of the dished knife, and said slots and bolts being arranged to adjust said housing 100 and knife to place the plane of the cutting edge of said knife at different angles with respect to the edge of said table.

In testimony whereof I have signed my name to this specification.

PATRICK J. LUCEY.
